STRING GALVANOMETER

Frederic O. Hindle, Milford, Conn., assignor to
The American Scientific Instrument Company,
Milford, Conn., a corporation of Connecticut

Application February 27, 1933. Serial No. 658,782

15 Claims. (Cl. 171—95)

This invention relates to new and useful improvements in string galvanometers, and has particular relation to improvements in the type of instrument disclosed in my prior Patents Nos. 5 1,416,824 of May 23, 1922 and 1,702,650 of February 19, 1929, and is intended especially for use in the Electro-cardiograph, although it is not limited to this use.

An object of the invention is to provide a 10 string galvanometer including a pole piece construction whereby the pole pieces are permanently secured together against any relative movement.

Another object is to provide an improved method of manufacturing and mounting the pole pieces 15 for a string galvanometer.

A further object is to provide a string galvanometer including means mounting the electro conductive string member and means so securing 20 the mounting means that it may be easily and quickly removed and another substituted should a string break or should another string for any other reason be required.

A still further object is to provide an improved 25 construction whereby it is not necessary to bore out the centers of the poles of the magnets to receive the microscope tubes with the consequent reduction in field strength.

An additional object is to provide a string galvanometer of generally improved construction including an improved base or mounting means and improved and simplified means for mounting the 30 parts thereon.

Other objects and advantages will become apparent from a consideration of the following detailed description taken in connection with the 35 accompanying drawings wherein a satisfactory embodiment of the invention is shown. However, it will be understood that the invention is not limited to the details disclosed but includes all such variations and modifications as fall within the spirit of the invention and the scope of the appended claims.

In the drawings:

45 Fig. 1 is a front elevational view of the improved device, parts being broken away to show details of construction;

50 Fig. 2 is a transverse vertical sectional view taken substantially along the line 2—2 of Fig. 1;

Fig. 3 is a view partly in section and partly in elevation, the view being taken substantially along the lines 3—3 of Fig. 1;

55 Fig. 4 is a sectional view taken substantially along the line 4—4 of Fig. 3;

Fig. 5 is a front elevational view of the base or mounting member alone;

Fig. 6 is a bottom plan view of the base with the magnet pole pieces in place thereon;

Fig. 7 is a perspective view of the pole pieces; 60

Fig. 8 is a transverse sectional view illustrating a step in the manufacture of the pole pieces;

Fig. 9 is a sectional view through the completed pole pieces;

Fig. 10 is a view somewhat similar to Fig. 8 but 65 showing a modified construction; and

Fig. 11 is a perspective view of a portion of a field magnet employed.

Referring in detail to the drawings, my improved instrument includes a base or mounting 70 means generally indicated at 12 and best shown in Figs. 5 and 6. This mounting member includes a plate-like portion 13 preferably in the form of a casting of non-magnetic metal, as for example aluminum. Integral with the plate 13 75 and extending nearly from end to end thereof, at a point midway between its side edges, is a raised portion or rib 14 slightly hollow or grooved in its upper surface to provide flanges 15 the purpose of which will later appear. Substantially centrally or in other location as desired the member 12 is provided with an opening 16 for the passage of a screw or other fastening means, and adjacent the respective ends of the rib 14 openings or screw holes 17 are provided 80 and the purpose of these openings will later be fully set forth.

At diametrically opposite points on the side edges of the plate 13 and in parallel relation with the rib 14 and with one another a pair of 90 outwardly extending projections or bearing members 18 and 19 are provided each of said projections being hollow or formed with an opening therethrough, the opening 20 in the outer portion of each projection being of greater diameter than 95 the opening 21 in the inner portion thereof. Later in the description of the assembled device the functions of these parts will be made clear. Strengthening ribs 22 are formed on the inner surface of plate 13 and connect with the end portions of the rib 14, and other strengthening ribs 23 are similarly formed on the plate 13 and connect the intermediate portion of the raised portion or rib 14 with the projections or bearing members 18 and 19. 100

According to the present invention pole pieces 24 and 25 are so constructed and connected as to form substantially a solid unit wherein the said pole pieces can have absolutely no relative move- 105

ment. To attain the most efficient way of causing the magnetic flux to concentrate at the center it is well known that these pole pieces should be substantially wedge shaped in transverse section 5 and should be arranged with their narrow edges in opposed relationship. In manufacturing the pole pieces I take a cross sectionally square or rectangular bar 26 (see Fig. 8) of magnetic material as iron and mill or cut away a portion 10 thereof to provide a V-shaped groove 27 the angle of the side walls of which may be anything desired but usually is approximately 45°. The apex of this groove is located slightly to one side of the center of the bar 26.

15 Next, according to one method, I weld together the two walls of the groove 27 as by depositing welding material (non-magnetic metal such as bronze) 28 in said groove until it is entirely or substantially entirely filled as best shown in Fig. 9. The magnetic bar 26 is first heated to a point that as the metal 28 is melted and deposited it adheres firmly to the iron and forms a body fused to and forming a weld between the side walls of the groove 27 whereby said walls are rigidly and permanently connected. This process is continued until the groove is filled with the non-magnetic metal and a substantially integral structure provided. Thereafter, (see Fig. 9) a similar groove 29 is formed in the opposite side 20 of said bar of magnetic metal and on the completion of the groove 29 a saw or other slot 30 is provided separating the remaining portions of the bar into the pole pieces 24 and 25. This slot 30 may extend slightly into the non-magnetic metal 28 and is of a width to properly space the 25 said pole pieces.

Another method of making this pole member is to clamp the two triangular pole pieces 24 and 25 in their proper relative positions in a suitable support and then fill in the groove at one side with the non-magnetic weld metal 28 as described.

As an alternative method (see Fig. 10) after the groove 27 is formed, or the two triangular pole pieces clamped in proper relation, a block 31 of non-magnetic metal, as for example brass, bronze, or the like, may be secured or fused in position filling the groove, as by brazing, the hard connecting brass or solder being indicated 40 at 32. According to this method the solid bar would then be grooved in its opposite surface and sawed or otherwise cut through to separate its remaining portions into pole pieces spaced the proper distance apart. In each instance the 45 magnetic pole pieces are so connected as to form a unitary structure in which these pole pieces would be incapable of relative movement as they are welded together.

The unitary pole piece structure made as 50 above set forth may now be provided with tapped recesses 33 arranged one in the outer face of each pole piece adjacent each end thereof. Also, aligned openings 34 and 35 are provided in the pole pieces the centers of these last openings being in alignment with the center of the slot or space 30 formed between the pole pieces as above 55 described. It will be apparent that the tap openings 33 and if desired the aligned openings 34 and 35 may be provided in the bar 26 before such 60 bar is treated to form the pole pieces.

The pole piece unit constructed as above described is arranged on the rib 14 with its non-magnetic body portion 28 disposed against the outer surface of said rib and the unit is of such 65 width as to fit snugly between the flanges 15 of

the rib whereby the unit is held against lateral movement. A screw 36 is then passed through the opening 16 in plate 13 and threaded into a tapped opening 37 in the portion 28 of the pole piece unit, or additional screws may be provided, whereby said unit is drawn tightly against the face of the rib 14 and held against movement outwardly of the flanges 15 of said rib. From this it will be seen that the unit is easily mounted and is firmly held against any movement relative to plate or base 13.

Pairs of coils 38 and 39 are arranged at the respective ends or adjacent the respective ends of the pole pieces and one coil of each pair is arranged at the outer side of the pole piece 24 90 while the remaining coils are arranged at the outer side of the pole piece 25. The coils enclose cores 40 through which extend screws or bolts 41 having their inner ends threaded into the tapped openings 33 before referred to. A substantially U-shaped or horseshoe field piece 42 is arranged at each end of the device or instrument and adjacent the free end of each of its arms each of said field pieces is provided with an opening 42a through which the screws 41 100 extend whereby said field pieces are mounted with their ends in close relation to the cores and with the cores clamped between said ends and the pole pieces. With this arrangement any stress or strain resulting from the strong magnetic force present when the machine is operating will not be required to be taken up by the parts 42 and their connections and will not result in any relative movement between the pole pieces 24 and 25.

Improved means are provided for supporting an electro conductive string member 43 in the space 30 between the opposed pole pieces 24 and 25. This means as here shown includes an elongated block or strip 44 of insulating material as for example bakelite or the like. At its inner side and between its ends the strip 44 carries an elongated block 45 to the upper end of which is secured an insulating block 46 having a metal contact member 47 thereon and to which is secured one end of the string 43.

Adjacent its lower end the block 45 is provided with a slot snugly receiving the outer end portion of a flat spring member 48, the inner or projecting end of which is loaded or strengthened 125 as at 49. Attention is particularly directed to the fact that there is but a very short portion of the spring exposed between the member 49 and the block 45 and torsional flexing of the spring is therefore reduced to a minimum. Secured to 130 the upper side of the inner end of spring 48 is the short arm 50 of a substantially L-shaped member, the long arm 51 of which extends upwardly at the inner side of the block 45. This long arm is provided with an opening through 135 which passes the inner end of a screw 52 whereby the member is held against lateral movement. As indicated above as the free portion of spring 48 is short this lateral movement of arm 51 is also practically prevented independently of screw 140 52. This insures the conductor string 43 will not be thrown laterally or out of center when its tension is adjusted.

The lower end of string member 43 is secured to the short arm 50 of the L-shaped member and 145 passing through the strip 44 and the block 45 is a screw 53 the inner end of which engages the upper end portion of arm 51. This screw 53 includes an operating head 54 at the outer side of mounting strip 44 and it will be understood 150

that by adjusting this screw the long arm of the L-shaped member may be pressed inwardly to rock said member by flexing the spring 48 whereby the short arm of the member will be moved 5 downwardly. This, of course, will result in increasing the tension of the string member 43.

A plate 55 (see Fig. 3) is secured to the outer side of each of the pole pieces 24 and 25 as by screws 56, and at their inner edges these plates 10 abut the outer edges of the flanges 15, and at their outer edges these plates fit into grooves provided for that purpose in the supporting strip 44. These plates serve to assist in properly positioning the supporting means for the string member where- 15 by to locate said string member in the space 30 between the opposing faces of the pole pieces. Additionally, a leg or arm member 57 is secured to the inner side of the strip 44 adjacent each of its ends, and these arm members are of a width 20 to snugly fit between the flanges 15 on the rib 14 and are of such length that when they engage the upper surface of said rib 14 the parts are so arranged that the string member 43 is properly located within the space between the pole pieces. 25 The strip 44 and the parts carried thereby form the support for the electro conductive string member 43, and to secure this support in place screws 59 are passed through the openings 17 in the base, and at their inner or forward ends are threaded 30 into the said strip as best shown in Fig. 2. Ob- 35 viously, should the string member break, the screws 59 may be retracted and the entire support for the string member lifted from the device. A second support having a string member properly mounted thereon may then be readily applied and secured in place by a tightening of the screws 59. The string members may be properly located on the supports at the factory and one or more extra supports kept on hand by the user who may 40 then readily replace a support should its string break or should it be desired to replace it for any other reason. No skill is required in mounting or dismounting a support from the device, and therefore much time and trouble is saved by the 45 user over the old devices where if a string conductor broke a new one had to be mounted and centered, which was a very delicate and long tedious operation.

Extending through the projection or bearing 18 and centered therein as by screws 60 is a micro- 50 scope 61. The inner end portion of this micro- scope is arranged in the opening 35 in the pole piece 24 and the microscope is focused on the string member 43. A second microscope 62 is 55 mounted in the bearing member 19 and is cen- tered therein as by the screws 63. This micro- scope 62 has its inner end portion located in the opening 34 through the pole piece 25 and is also focused on the string member 43. It will be 60 noted that with the arrangement of the pole pieces and the coils and their cores as above de- 65 scribed and illustrated it is not necessary to bore out the magnets to receive the microscope with consequent reduction in field strength, but there is required only a small hole 34 or 35 in the center of the magnet pole pieces to admit the microscope. In the use of the machine a bright white light is focussed on the string by one micro- 70 scope, as for example the microscope 61, and the shadow cast by the string member is picked by the second microscope and enlarged and passed to any suitable camera means, not shown, oper- 75 ating with a sensitized strip. The use of the machine in making charts is fully understood and fully disclosed in the prior art and a further de-

scription thereof is believed unnecessary. The leads from a suitable source of exciting current and the leads for the current to be measured or recorded are connected to the magnet coils and the string conductor respectively in the usual 80 manner.

From the foregoing description taken in connection with the drawings it will be appreciated that I have provided a string galvanometer of a simplified construction. Further, it will be noted 85 that the device is not of the usual extremely heavy construction heretofore employed for the purpose of holding the magnet pole pieces against relative movement. By the method disclosed the pole pieces are so secured together as to form a rigid 90 strong unit wherein relative movement between the pole pieces is impossible. With the present construction the parts are few and easily assem- bled and in the event of the breakage of a string member the entire string support may be easily 95 and quickly removed and another support and string substituted.

Heretofore, heavy constructions have been em- 100 ployed in devices of this kind. In the present device the field pieces 42 are not secured directly to the plate or support 13 and are held in place solely by the screws 41. Further, the ends of these pieces 42 do not abut the edges of the pro- 105 jections 18 and 19 but are spaced slightly there- from whereby movement resulting from the ap- plication of current to the coils is permitted by the field pieces without displacing the pole pieces or the string conductor.

It will thus be evident that with my improved 110 construction the pole faces are held rigid in per- fect alignment with the microscopes. The pole faces are also held a certain fixed distance apart and they may be placed close together to secure maximum magnetic flux. It has heretofore been 115 impossible to economically construct a means of holding the magnetic pole pieces immovable due to the tremendous attraction of the two pole pieces when under the magnetic strain. This was a serious difficulty as any movement of the pole pieces or their faces will cause misalignment 120 of the microscopes or the string conductor. The shifting of either of these component parts causes difficulties in using the instrument. These difficulties are effectively overcome in my 125 improved device as the pole pieces are in effect integral with each other and are mounted on the non-magnetic metal frame, the microscopes are mounted on the same frame and the mag- netic cores for the coils, and the connecting field pieces are attached to the pole faces only. 130 Therefore any distortion or magnetic striction is absorbed by the yielding of the field pieces.

Having thus set forth the nature of my inven- 135 tion, what I claim is:

1. In a galvanometer, a pair of pole pieces of magnetic material wedge shaped in cross section arranged with a pair of their narrower edges in opposed spaced relation, and non-magnetic metal filling the space between a pair of side walls of said pieces and fused to these walls to 140 provide a unitary structure.

2. In a galvanometer, an electro magnet hav- 145 ing opposed spaced pole pieces, an electro con- ductive string member, means supporting said member with the member disposed in the space between said opposed pole pieces, each of said pole pieces wedge-shaped in transverse section and said pole pieces disposed with their narrower portions in opposed relation, means holding said pole pieces against relative movement, and said 150

- means comprising a body of non-magnetic material fused to each of said pole pieces.
3. In a galvanometer, a base member having a grooved portion, an electro magnet comprising a pair of opposed slightly spaced pole pieces, each of said pole pieces wedge shaped in transverse section and said pole pieces disposed with their narrower edges in opposing relation, means holding said pole pieces against relative movement and substantially filling the space between them at their undersides, said means comprising a body of non-magnetic material fused to said pole pieces whereby to form them into a unit, said unit disposed in and snugly fitting between the walls of the groove in said base portion, means engaging said unit and holding it in said groove, an electro conductive string member, and means supporting said string member in the space between said pole pieces.
- 20 4. In a galvanometer, an electromagnet comprising opposed spaced pole pieces, each of said pole pieces wedge shaped in transverse section and said pole pieces disposed with their narrower edges in opposing relation, means holding said pole pieces against relative movement and substantially filling the space between them at their undersides, and said means comprising a body of non-magnetic material fused to each of said pole pieces whereby to form them into a unit.
- 30 5. The method of forming a rigid unit including a pair of transversely wedge shaped opposed pole pieces arranged in spaced relationship with their narrower edges in opposed relation, the same comprising providing a bar of magnetic material, forming a V-groove in one side of said bar, filling said groove with non-magnetic metal fused to the walls of the groove, forming a similar groove in the opposite side of said bar, and then cutting through the remaining portion of the bar at the apex of said second groove.
- 40 6. The method of forming a rigid unit including a pair of transversely wedge shaped opposed pole pieces arranged in spaced relationship with their narrower edges in opposed relation, the same comprising providing a bar of magnetic metal, forming a V-groove in one side of said bar, filling said groove with non-magnetic metal by depositing molten non-magnetic metal therein whereby to weld together the walls of said groove, forming a similar groove in the opposite side of said bar, and then cutting through the remaining portion of the bar at the apex of said second groove.
- 50 7. The method of forming a rigid unit including a pair of transversely wedge shaped opposed pole pieces arranged in spaced relationship with their narrower edges in opposed relation, the same comprising providing a bar of magnetic metal, forming a V-groove in one side of said bar, filling said groove by brazing to the walls thereof a wedge shaped block of non-magnetic metal, forming a similar groove in the opposite side of said bar, and then cutting through the remaining portion of the bar at the apex of said second groove.
- 60 8. In a galvanometer, a base or mounting member, said member comprising a plate-like portion of non-magnetic metal, a centrally located raised portion on said plate, a pair of outwardly directed parallel projections on said plate and arranged at diametrically opposite points thereon and at the sides of said raised portion, opposed slightly spaced pole pieces mounted on said raised portion, a pair of coils at each end of said plate and arranged one at each side of and closely adjacent said pole pieces, a substantially U-shaped field piece at each end of said plate and each having its respective ends disposed at the outer end of one of said pairs of coils, a bar passing through each of said coils and mounting the same, said bars having their outer ends secured to the adjacent ends of said field pieces and having their inner ends secured to one of said pole pieces, an electro conductive string member, means supporting said member to dispose it between said pole pieces, aligned openings through said pole pieces, a telescope mounted in each of said projections, and said telescopes focussed on said string member through the openings in the pole pieces.
- 80 9. In a galvanometer, a mounting member, said member including a plate-like portion of non-magnetic metal, opposed spaced pole pieces mounted on said plate, a pair of coils adjacent each end of said pole pieces, said coils at the respective ends of the pole pieces arranged one coil at the outer side of and closely adjacent each of said pole pieces, a substantially U-shaped field piece arranged toward each end of said plate, said field pieces at the respective ends of the plate having their ends disposed at the outer ends of the coils adjacent the respective ends of the plate, a bar connected to each of said field piece ends and passing through the adjacent coil and into the adjacent pole piece whereby to mount the field pieces and coils, an electro conductive string member, and means supporting said member to dispose it in the space between said pole pieces.
- 90 10. In a galvanometer, a mounting member, a pair of parallel spaced flanges on said member and forming a groove, a pair of opposed spaced pole pieces on said member, a support, an electro conductive string member mounted on said support, a pair of arms on said support and adapted to enter said groove and engage the bottom thereof to dispose said string member in the space between said pole pieces, and means to secure said support to said mounting member with said arms in said groove and engaging the bottom thereof.
- 100 11. In a galvanometer, a mounting member, a pair of parallel spaced flanges on said member and forming a groove, a pair of opposed spaced pole pieces on said member, a support, an electro conductive string member mounted on said support, a pair of arms on said support and adapted to enter said groove and engage the bottom thereof to dispose said string member in the space between said pole pieces, and screws passing through said mounting member and into said support and securing said support to the mounting member with the ends of said arms drawn tightly into engagement with the bottom of said groove.
- 110 12. In a galvanometer, a mounting member, a pair of opposed spaced pole pieces on said member, a support, an electro conductive string member, means mounting said string member on said support, said means disposed at the inner side of said support and including an L-shaped member, a short flat spring having the short arm of said L-shaped member rigidly secured thereto, said string member having one end secured to the short arm of said L-shaped member, means engaging the other arm of said L-shaped member and adjustable to rock it by flexing said spring to tension said string member, and means to secure said support to said mounting member with said string member disposed in the space between said pole pieces.
- 120 13. In a galvanometer, a mounting member, a pair of parallel spaced flanges on said member

- and forming a groove, a pair of opposed spaced pole pieces on said member, a support, an electro conductive string member, means mounting said string member on said support, said means disposed at the inner side of said support and including an L-shaped member, a short flat spring having the short arm of said L-shaped member rigidly secured thereto, said string member having one end secured to the short arm of said L-shaped member, means engaging the other arm of said L-shaped member and adjustable to rock it by flexing said spring to tension said string member, a pair of arms on said support and adapted to enter said groove and engage the bottom thereof to dispose said string member in the space between said pole pieces, and means to secure said support to said mounting member with said arms in said groove and engaging the bottom thereof.
- 10 14. In a galvanometer, a mounting member, a pair of opposed spaced pole pieces on said member, a support, an electro conductive string member, means mounting said string member on said support, said means disposed at the inner side of said support and including an L-shaped member, a short flat spring having the short arm of said L-shaped member rigidly secured thereto, said string member having one end secured to the short arm of said L-shaped member, means
- 30 engaging the other arm of said L-shaped member and adjustable to rock it by flexing said spring whereby to tension said string member, said means including a screw extending through said support and operable from the outer side thereof, and means to secure said support to said mounting member with said string member disposed in the space between said pole pieces.
- 35 15. In a galvanometer, a mounting member, said member comprising a plate-like portion of non-magnetic metal, a centrally located raised portion on said plate, said raised portion grooved in its outer surface to provide a pair of parallel flanges, a unit comprising a pair of opposed spaced transversely wedge-shaped pole pieces connected at their undersides by a body of non-magnetic metal fused to them, said unit disposed on said raised portion of the mounting member and snugly fitting between the walls of the groove thereof, a screw passing through said mounting member and into said body of non-magnetic material and serving to draw said unit tight against the bottom of said groove, field magnets associated with said pole pieces, an electro conductive string member, and means supporting said string member in the space between said pole pieces.
- 40 16. In a galvanometer, a mounting member, a pair of opposed spaced pole pieces on said member, a support, an electro conductive string member, means mounting said string member on said support, said means disposed at the inner side of said support and including an L-shaped member, a short flat spring having the short arm of said L-shaped member rigidly secured thereto, said string member having one end secured to the short arm of said L-shaped member, means
- 45 17. In a galvanometer, a mounting member, a pair of opposed spaced pole pieces on said member, a support, an electro conductive string member, means mounting said string member on said support, said means disposed at the inner side of said support and including an L-shaped member, a short flat spring having the short arm of said L-shaped member rigidly secured thereto, said string member having one end secured to the short arm of said L-shaped member, means
- 50 18. In a galvanometer, a mounting member, a pair of opposed spaced pole pieces on said member, a support, an electro conductive string member, means mounting said string member on said support, said means disposed at the inner side of said support and including an L-shaped member, a short flat spring having the short arm of said L-shaped member rigidly secured thereto, said string member having one end secured to the short arm of said L-shaped member, means
- 55 19. In a galvanometer, a mounting member, a pair of opposed spaced pole pieces on said member, a support, an electro conductive string member, means mounting said string member on said support, said means disposed at the inner side of said support and including an L-shaped member, a short flat spring having the short arm of said L-shaped member rigidly secured thereto, said string member having one end secured to the short arm of said L-shaped member, means
- 60 20. In a galvanometer, a mounting member, a pair of opposed spaced pole pieces on said member, a support, an electro conductive string member, means mounting said string member on said support, said means disposed at the inner side of said support and including an L-shaped member, a short flat spring having the short arm of said L-shaped member rigidly secured thereto, said string member having one end secured to the short arm of said L-shaped member, means
- 65 21. In a galvanometer, a mounting member, a pair of opposed spaced pole pieces on said member, a support, an electro conductive string member, means mounting said string member on said support, said means disposed at the inner side of said support and including an L-shaped member, a short flat spring having the short arm of said L-shaped member rigidly secured thereto, said string member having one end secured to the short arm of said L-shaped member, means
- 70 22. In a galvanometer, a mounting member, a pair of opposed spaced pole pieces on said member, a support, an electro conductive string member, means mounting said string member on said support, said means disposed at the inner side of said support and including an L-shaped member, a short flat spring having the short arm of said L-shaped member rigidly secured thereto, said string member having one end secured to the short arm of said L-shaped member, means
- 75 23. In a galvanometer, a mounting member, a pair of opposed spaced pole pieces on said member, a support, an electro conductive string member, means mounting said string member on said support, said means disposed at the inner side of said support and including an L-shaped member, a short flat spring having the short arm of said L-shaped member rigidly secured thereto, said string member having one end secured to the short arm of said L-shaped member, means
